J. M. McNEILL

GRAVE MARKER

Filed Oct. 1, 1923

UNITED STATES PATENT OFFICE.

JOHN MALCOLM MCNEILL, OF ST. JOSEPH, MISSOURI.

GRAVE MARKER.

Application filed October 1, 1923. Serial No. 665,923.

To all whom it may concern:

Be it known that I, JOHN M. MCNEILL, a citizen of the United States, and a resident of St. Joseph, in the county of Buchanan and State of Missouri, have invented a new and useful Improvement in Grave Markers, of which the following is a full, clear, and exact description.

My invention relates to improvements in grave markers, and it consists in the combinations, constructions, and arrangements herein described and claimed.

An object of my invention is to provide a grave marker of the character described that is simple in construction, and that may be manufactured at a minimum cost.

A further object of my invention is to provide a grave marker of the character described by means of which the identity 20 of the deceased may be clearly preserved for the duration of the life of the marker. It is often impossible to provide a stone or marker of other imperishable material upon which the identity of the deceased may be 25 cut, and at the present time, various forms of markers constructed of wood and the like are employed upon which the identity of the deceased is imprinted, but in which the imprint is exposed to the destructive 30 influences of the elements.

A further object of my invention is to provide a grave marker of the character described in which the legends contained thereon may be changed at will.

A further object of my invention is to provide a grave marker of the character described which may be easily set in the ground adjacent the grave without necessitating the provision of an opening for receiving the base of the marker.

Other objects and advantages will appear in the following specification, and the novel features of the invention will be particularly pointed out in the appended claims.

My invention is illustrated in the accompanying drawings, forming part of this application, in which—

Figure 1 is a front elevation of an embodiment of my invention,

Figure 2 is a sectional view along the line 2—2 of Figure 1,

Figure 3 is a rear elevation of the mechanism illustrated in Figure 1, and

Figure 4 is an enlarged view of a portion 55 of the mechanism illustrated in Figure 2.

In carrying out my invention, I make use

of a metal face plate 1 rounded at its upper end 2 and tapering to a relatively sharp point at its lower end 3. The face plate 1 has an angular aperture 4 therethrough 60 adjacent its upper end (see Figure 1).

The face plate 1 is further provided with an angular flange 5 extending rearwardly thereof and in close proximity with the inner edges of the opening 4. A transparent 65 glass window 6 is disposed within the angular flange 5 to close the opening 4 from wind, rain, and other destructive elements. In order to further the sealing of the opening 4, I provide a rubber gasket 7 which 70 is disposed between the rear wall of the face plate 1 and the window 6.

A block 8 for supporting removable letters 9 by means of which legends may be inscribed on the marker is fitted within the 75 adjacent inner walls of the flange 5 and permitted to contact the inner walls of the glass member 6. The block 8 is of sufficient thickness to project beyond the rearward edge 10 of the flange 5.

Means for securely fixing the block 8 in position against the glass window 6 so as to exert a slight pressure thereupon and subsequently upon the gasket 7, is provided in a metal covering 11 arranged to encompass 85 and closely contact with the outer side walls of the flange 5 and the rear wall of the block 8. The flange 5 is provided with a protrusion 12 on its outer wall. This protruded portion 12 is arranged to be received in a cavity 13 formed in the bottom wall of the cover 11. The upper end of the cover 11 is provided with an upwardly extending plate 14 which is arranged to lie in close proximity with the rear wall of the face 90 plate 1. Obviously, the cover 11 may be removed from the flange 5 by merely grasping the portion 14 and drawing it away from the face plate.

The block 8 is provided with a plurality 100 of longitudinally extending grooves 15 therein. Each of the grooves 15 has an angular enlargement 16 at the bottom thereof and a relatively narrow cavity 17 at its upper sides extending toward the rear portion of the block 8. The adjustable letter plates 9, substantially L-shaped in cross section, are fitted in the grooves 15 to form legends relating to the deceased, whereby the identity of the deceased may be made 110 known.

Obviously, letters having the cross sec-

tion, as shown at 9 in Figure 4, or flat plates, as shown at 17 in the last two grooves of the block 8 shown in Figure 4, may be used. It will be understood of course that 5 the particular structure of the letter plates is entirely at the option of the user.

From the foregoing description of the various parts of the device, the operation thereof may be readily understood. In order to fix the letters to the marker, it is merely necessary to move the cover 11 in the manner heretofore described, which consists in drawing the portion 14 away from the face plate 1. The block 8 may thereupon 15 be extracted from within the walls of the flange 5 and the letter plates 9 or 17, as the case may be, adjusted in the grooves 15. When this is done, the block 8 is reinserted in its position within the walls of the flange 20 5 and the cover plate 11 replaced. It will be noted that the cover plate causes the glass 6 to bear against the gasket 7 in such a manner as to render the space between the block 8 and the wall of the face plate 1 25 water-tight.

The marker may be fixed in its place by

merely forcing the pointed end 3 of the marker into the earth in much the same manner as the ordinary stake.

I claim:

1. A grave marker of the character described comprising a rigid plate adapted for engagement with the earth adjacent the grave, said plate having an opening therethrough, a transparent window disposed in said opening, a block disposed at the rear of said window, means associated with said block for displaying legends relating to the deceased through said window, and a waterproof covering for the block.

2. A grave marker of the character described comprising a rigid plate adapted for engagement with the earth adjacent the grave, said plate having an opening therethrough, a gasket disposed concentric with said opening, a transparent window disposed in said opening, a block disposed at the rear of said window, means associated with said block for displaying legends relating to the deceased through said window, and a waterproof covering for the block.

JOHN MALCOLM McNEILL.
